M. E. MITCHELL

SIGNALING DEVICE

Filed Jan. 12, 1925

49 INVENTOR.
MALCOLM E. MITCHELL
BY *Malcolm E. Mitchell & Co.* ATTORNEYS.

UNITED STATES PATENT OFFICE.

MALCOLM E. MITCHELL, OF ALAMEDA, CALIFORNIA, ASSIGNOR OF ONE-HALF TO
DAVID GARFINKLE, OF ALAMEDA, CALIFORNIA.

SIGNALING DEVICE.

Application filed January 12, 1925. Serial No. 2,001.

The present invention relates to improvements in signaling devices for motor vehicles, and has particular reference to a means for making the customary signals given by the 5 left arm of the driver more conspicuous. It is proposed to utilize for this purpose an electric lamp, or other electrically operated signaling device that is normally seated near the steering post within convenient reach of 10 the driver, and that may be gripped by the latter when he wishes to extend his arm for the purpose of giving a signal and carried by the signaling arm into the proper signaling position, means being provided in connection therewith for allowing the said signal to automatically return to its seat when the arm is withdrawn.

It is further proposed in connection with this means to provide means causing the 20 electric lamp to light when guided into a signaling position and to become automatically extinguished when returned to its seat.

For this purpose it is proposed to secure the lamp or whatever other electrical signaling device may be used at the end of a cord containing flexible conductors and adapted to be wound on a spring operated drum when at rest, means being provided in combination therewith for allowing the lamp 30 returning to its seat to turn off a switch controlling the electrical circuit lighting the lamp.

Further objects and advantages of my device will appear as the specification proceeds.

The preferred form of my invention is illustrated in the accompanying drawing, in which—

Figure 1 shows my signaling lamp in actual use on an automobile.

Figure 2 a front view of my device with the signaling lamp seated, a portion of the cover being broken away to disclose the interior.

Figure 3 a section taken along line III— 45 III of Figure 2.

Figure 4 a section taken along line IV— IV of Figure 2, and

Figure 5 a side view of the mounting means for the lamp with the lamp itself 50 omitted.

While I have shown only the preferred form of the invention, it should be understood that various changes or modifications

may be made within the scope of the claims hereto attached without departing from the 55 spirit of the invention.

The lamp 1 is suitably mounted in a sleeve socket 2 which latter may be secured by means of a bayonet joint 3 to the plug 4 adapted to be seated and the seat 6 extending from the periphery of a cylindrical casting 7 which latter consists of two sections 8 and 9 adapted to be fastened upon one another by means of screws 11.

The casing has two slotted flanges 12 projecting from its hub portion in opposite directions, the flanges running parallel to one end of the case and being adapted for engagement by two bolts 13 adapted to straddle the steering post 14 and allowing the 65 case to be clamped to the latter by means of nuts 16 bearing upon a plate 17 curved to engage the steering post from the opposite side.

Internally the case is provided with an 70 axial sleeve 18 extending from one of the two sections thereof into contact with the other section and surrounding the screw 11 previously mentioned. Inside of the case so as to be revolvable on the sleeve 18 is the 75 drum 19 which also consists of two sections 21 and 22, the latter being a disk with a central aperture 23 and the former being a disk indented in its central portion so as to form the bottom 24 of a groove and provided with 80 a hub 26 adapted to revolve on the sleeve 18. The aperture 23 in the disk 22 is sufficiently large to clear the hub 26 of the other disk so that there is no electrical communication 85 between the two disks, an insulating sheet 90 29 being interposed between the same and small bolts 31 used for fastening the two disks upon one another being also insulated from the disk 22 as shown at 95 32. The indented portion of the disk 21 forms an annular pocket 33 adapted to receive a spring 34, one end of which is secured to the sleeve 18 of the case, as shown at 35, and the other end of which is secured to the inner face of the disk 21, as shown at 40.

The drum 19 thus formed by the two disks has a cord 36 wound thereon which latter has two wires 37 and 38 hidden therein, one of the wires being fastened to the section 21, as shown at 39, and the other to the 100 section 22, as shown at 41. The free end 105

of the cord connects with the plug 4 and the two wires of the cord are electrically connected to the filament of the lamp 1 in a manner well known in the art and therefore not illustrated.

The section 21 is grounded through its contact with the sleeve 18. The case 7 is enlarged near the seat 6 so as to form a chamber 42 in which is pivoted a lever 43, as shown at 44, the long end of the lever extending into operative proximity to the plug 4 so as to be forced inwardly by the latter when the same is seated while the other end of the lever carries in an insulating plug 46 and a contact 47 adapted to be forced upon the periphery of the disk 22 by means of a spring 48 when the plug 4 is removed from its seat and thereby allows the lever 43 to swing on its pivot. The contact 47 connects with a wire 49 which leads to any suitable source of energy, such as a battery, the other terminal of which is grounded to complete the circuit.

The operation of my device is as follows: The spring 34 tends to remove the drum formed of the two disks 21 and 22 so as to wind the cord 36 on the drum between the extremities of the two disks, whereby the plug 4 is forced upon its seat 6 which is its normal position. The plug bears upon the long end of the lever 43 and thereby throws the contact 47 away from the periphery of the disk 22 so that the circuit is broken. When the driver desires to give a signal by extending his left arm to project outside of the body of the motor vehicle, he first grasps the sleeve 2 of the lamp and causes the lamp to follow the motion of the arm so as to be visible to pedestrians or the drivers of other machines. In doing this he causes the cord 36 to unreel from the drum and places the spring 34 under tension while at the same time allowing the spring 48 to force the contact 47 upon the periphery of the disk 22 whereby the circuit is closed. When the proper signal has been given, the driver draws back his arm and allows the spring 34 to retract the lamp to its seat which causes the plug 4 to bear on the lever 43 for disengaging the contact 47 from the periphery of the disk 22.

The electrical circuit is easily understood from the drawing, the same comprising a source of energy such as a battery, the wire 49, the contact 47, the disk 22, the two wires 38 and 37 connected to the filaments of the lamp, the second disk 19 and a ground connection between the latter and the battery.

I claim:

1. In a signaling device, a casing formed with a seat structure upon the outside thereof, a drum comprising two metallic sections insulated from each other, a cord wound on the drum comprising two wires connected to the two sections respectively,

a signaling element connected to the two wires and formed for seating in said seat, yielding means urging the element upon its seat, a lever pivoted in the casing having a contact at one end adapted to contact with one of the sections and extending with the other end thereof into the path of the signaling element moving toward its seat for breaking the contact.

2. In a signaling device, a casing comprising two sections, a central hub extending from one of the sections toward the other and a screw bearing on the latter and threaded into the hub for holding the sections together and a drum comprising a disc having a central portion depressed to form a recess on one side, and a cylinder on the opposite side, and having a central sleeve, extending from said depression adapted to revolve on the hub, a second flat disc fastened to the depressed section, with insulating material interposed between the discs, a spring in the recess connecting the recessed disc to the hub, a cord wound on the cylinder between the peripheral portions of the discs, having two wires connected to the two discs respectively, a seat formed in the casing, a signaling element connected to the wires and adapted to be seated on said seat by the action of the spring and a contact lever pivoted in the casing and spring-actuated to normally contact one of the discs, and extending into the path of the signaling element moving toward its seat for breaking the contact.

3. In a signaling device, a casing, split transversely to form two sections, and having axial means holding the two sections together, a drum revolvable relative to the axial means having separable rim sections insulated from one another, wires wound on said drum and connected to the drum sections respectively, a signaling element connected to said wires, and spring means opposing unwinding of the wires.

4. A reel for a signaling device of the character described, comprising a disc formed with a central depression providing a recess on one side and a cylinder on the other side, a central sleeve extending from the depression, a flat disc perforated centrally to slip over the sleeve, insulation interposed between the discs and means for fastening one of the discs upon the other.

5. In a signaling device, of the character described, a casing comprising two separable sections with axial means for holding the same together, and a drum comprising two separable sections insulated from one another revolvable relative to the axial means, a spring arranged within the confines of one of the drum sections, and a cord wound on the drum so as to place the spring under tension when the cord is unwound.

MALCOLM E. MITCHELL.
